UNITED STATES PATENT OFFICE.

DUDLEY B. CLARK, OF BEMUS POINT, NEW YORK.

CIGAR-LIGHTER.

1,362,227.

Specification of Letters Patent. Patented Dec. 14, 1920.

Application filed August 6, 1920. Serial No. 401,686.

To all whom it may concern:

Be it known that I, DUDLEY B. CLARK, a citizen of the United States, residing at the village of Bemus Point, in the county of 5 Chautauqua and State of New York, have invented certain new and useful Improvements in Cigar-Lighters, of which the following, taken in connection with the accompanying drawings, is a specification.

10 The invention relates to electric lighters or igniters, the special use being shown as a tobacco lighter; and the object of the improvement is, first, to provide two resistances which are placed in series and connected to 15 an electric circuit of commercial standard voltage; the first resistance is the lighting or igniting element which is provided with ventilation through said cabinet, so that when a cigar is placed against said lighting 20 or igniting element and drawn upon, a light will be produced, and the second resistance is the series element; and the invention consists in the novel features and combinations hereinafter set forth and claimed.

25 In the drawings, Figure 1 is a perspective view of the cigar or tobacco lighter, showing the lighter head with its ventilating cap. Fig. 2 is a vertical diametral sectional view of the cigar or tobacco lighter at line 2—2 30 in Fig. 3 showing the preferred construction and arrangement of the parts; and Fig. 3 is a sectional view of the cigar and tobacco lighter at line 3—3 in Fig. 2 showing the ventilation through the rear of the 35 lighter case. Fig. 4 is a plan view of the lighter head, a portion of the rim cap being broken away to show the construction of the same, and the wire lighting element threaded through the insulating block in spiral arrangement; and Fig. 5 shows said spiral arrangement and the connections thereto; and Fig. 6 is a plan view of the insulation with the holes in circular arrangement therein ready to receive the wire resistance lighting element which is sewed through said 40 holes. Fig. 7 is a sectional view of the insulation blocks showing the manner in which the lighting element is connected through said blocks and the second resistance element to the source of supply for electricity. Figs. 8 and 9 show the heat and electric insulation blocks as provided on the lighter head; and Fig. 10 shows the spaced insulation sleeves which separate said blocks; and 45 Fig. 11 is a perspective view of the neck support for the lighter head which is turned

slightly to one side in order to provide a convenient angle of approach to the lighting element. Fig. 12 shows a slight modification of the wire lighting or igniting element in which the said element is arranged in the form of a concentric sunken coil on the face of the heat and electric insulation block; and Fig. 13 is a sectional view at line 13—13 in Fig. 12 showing the preferred construction and arrangement of said modification. Fig. 14 is a plan view of the under side of the block as shown in Figs. 12 and 13, showing the manner of connecting the coils of the wire lighting or igniting element.

Like characters of reference refer to corresponding parts in the several views.

The numeral 15 designates the casing which is preferably made of sheet metal. 75 The neck portion 16 is preferably a Monel metal tubular casting which is flanged around the base and attached by suitable bolts 17 to the top of the casing 15, and has its upper end turned slightly at an incline 80 to receive the lighting head 18 thereon at said convenient angle of approach.

The lighting head 18 is composed of the electrical and heat insulation blocks 19 and 21 which are separated by the insulation sleeves 20 around the attaching screws. The insulation block 21 is preferably molded from heat resisting material sufficiently strong to attain the purpose. The sleeves or cylinders 20 around the attaching screws 22 90 and 26 are preferably made from a strong heat insulating material, and permit the air to surround the block 21. The screw bolts 22 extend through the blocks 19 and 21 and sleeves 20 into threaded holes in the neck 95 portion 16, thereby firmly attaching the built-up lighting head 18 upon the inclined face of the neck portion 16.

The insulation block 21 is a heat resisting or fire-proof electrical insulating composition block which has a central sunken portion or recess 23 on its outer surface, having the holes 24 therethrough, the wire resistance lighting element 25 being sewn through said holes 24 and extending over the central 100 portion of the surface of the sunken portion 23. The wire lighting element 25 preferably consists of a resistance alloy, the ends of which are connected to the attaching bolts 26, which bolts 26 are connected in series by 110 the wire 27 to the momentary push switch 40 on the front of the casing 15 and to the

series element or resistance 29 and thence to the cord 30. A second connecting wire 28 runs direct from the other connecting bolt 26 to said cord 30 and through said cord to 5 a commercial lighting circuit or other source of electrical supply.

The insulation block 19 has the ventilating opening 38 therethrough for the purpose of supplying air from the interior of 10 the casing 15 to the small openings or holes 24 in the block 21 through which the resistance wire lighting element 25 is sewn. The wires 27 and 28 are preferably insulated with asbestos and when connected as 15 described, the resistance of the lighting element 25 and the series element 29 is so proportioned that said lighting element 25 will offer a greater resistance to the passage of 20 the current than said series element 29 and will come to an incandescent heat more quickly than said series element 29. By the time the lighting element 25 reaches said incandescent heat, the series element 29 will have heated sufficiently to increase its 25 resistance and thus lower the voltage on the lighting element 25 and act as an automatic check for the thermostatic control which tends to keep the lighting element from reaching excessive heat, yet when the 30 switch is first closed, this arrangement allows the lighting element 25 to become ignited quickly, and then automatically checks a dangerous rise of temperature.

As thus arranged, when a cigar is placed 35 against the lighting or igniting element 25 and drawn upon, said hot wire lighting element 25 as well as the air heated by passing through the fine holes 24 produce a heat which lights the cigar. The element 25 is 40 protected from any possible mechanical injury by means of a perforated mica plate 31 which is securely held in place by the bolts 22. A rim cover 32 is provided which fits over the outer edge of the block 19 and is 45 attached thereto by suitable screws, with the inner edge resting upon said mica plate 31, thereby aiding in holding it firmly in position. The perforations 33 in the mica plate 31 are preferably in the same general order 50 as the holes 24, so that the air draws through said mica plate 31 from about the resistance lighting element 25 thereby spreading the heat evenly over the diameter of the recess 23 in the block 21.

The fire-proof, heat resisting block 21 55 keeps the heat in the element 25 from heating back into the case 15. The round block 19 is preferably of hard asbestos material as stated, and supports the block 20 and 20 and rim 32. The heads of the bolts 26 are 60 preferably placed in the recess 23 and covered by the mica plate 31 so that there will be no danger of the edge of the rim 32 connecting with said bolt and thereby short-circuiting the element 25. Instead of the

resistance 29, a transformer might be used where an alternating current is available.

A modification of the lighting element is shown in Figs. 12 and 13 in which said lighting element is arranged as a spiral coil 70 34 which is sunken in a spiral groove 35 over the small holes or perforations 24, in which arrangement the said wire resistance lighting element is not sewn through said holes 24, but is merely arranged in a continuous coil in the spiral groove 35 as shown in Fig. 12. They may be used in concentric coils by being connected in series on the under side of the block and using the screws or screw bolts 22 as terminals, the same as 80 the preferred form 25 of the lighting element. The perforated metal rim 32 permits the escape of the heat through the perforations. It carefully guards the lighting element and protects the head as against 85 rough usage.

As hereinbefore described, when the lighter is connected to an electrical source of supply by means of the wires 27 and 28, all that is necessary is to place the end of 90 the cigar against the mica plate 31 and draw the heat through the perforations 33 therein, thereby quickly lighting the cigar end.

The casing or cabinet 15 has the ventilated openings 36 in the rear side and 39 in 95 the bottom, which with the opening 37 into the neck portion 16 and the ventilating openings 38 in the blocks 19 and 20 in combination with the minute perforations 24 in blocks 21 and 33 in the mica plate 31, permit 100 the free passage of the air through the casing 15 and lighter head 18 to the end of the cigar as it is pressed against the said mica plate 31. The hot wire element threaded through the perforations 24 heats the air as 105 it passes through each of said perforations, thereby aiding in the quick lighting of the cigar.

I claim as new:

1. A cigar lighter including a support, a 110 lower insulation block thereon, an upper insulation block, spaced insulation means between said blocks to space the latter apart, said upper block having a sunken center part, igniting means in the sunken center 115 part, a perforated mica plate on the upper part extending over the igniting means, means to energize the igniting means, and a cover secured to the periphery of the lower block and extending past the insulation 120 means and past the upper block in spaced relation to each and further extending above the upper block in spaced relation thereto and having its upper end extending inwardly and engaged on top of the mica plate, said 125 cover having openings throughout its sides and top.

2. A cigar lighter comprising two resistances placed in series and connected to an electrical lighting circuit of commercial 130

- standard voltage, one of said resistances a lighting or igniting element, said resistances proportioned to one another to give said lighting or igniting resistance a quick and 5 an initial higher temperature than the other resistance and the latter caused to act as a check against further increase in temperature of said lighting or igniting element upon desired heating of the latter.
- 10 3. In a cigar lighter, a pair of superposed insulation blocks, spaced means to hold said blocks spaced apart, igniting means on the upper block, and a cover spaced from the sides and the top of the upper block and having 15 perforations alining with the spaces between the blocks and between the spacing means thereof and with the space above the upper block, and means to energize the igniting means.
- 15 4. In a cigar lighter, a pair of superposed insulation blocks, spaced means to hold said blocks spaced apart, igniting means on the upper block, a perforated mica plate spaced above the igniting means, and a cover spaced 20 from the sides and the top of the upper block and having perforations alining with the space between the blocks and with the space above the mica plate, and means to energize the igniting means.
- 20 5. A cigar lighter comprising a lighter head, a heat resisting fire-proof insulation block on said head having a series of holes therethrough, a resistance lighting element sewn through said holes in said block and 25 connected to a source of electrical supply in series with a second resistance proportioned to said lighting element to give the same a higher temperature than said second resistance, and a perforate mica plate over 30 said lighting element to protect the same and draw the igniting heat therethrough.
- 35 6. In a cigar lighter, the combination in a lighting head of an electrical insulating heat resisting fire-proof block on said head having 40 a series of holes therethrough, a resistance lighting element sewn through said holes in said block and connected to a source of electrical supply in series with a second resistance proportioned to said resistance 45 lighting element to give the same a higher initial temperature than said second resistance, said block supported in said head on insulation sleeves to permit the free circulation 50 of air on all sides of the same.
- 55 7. In a cigar lighter, the combination in a lighting head of an electrical insulating heat resisting fire-proof block on said head having a series of holes therethrough, a resistance lighting element sewn through said holes in said block and connected to a source of electrical supply in series with a second resistance proportioned to said resistance lighting element to give the same a higher initial temperature than said second resistance, said block supported in said head on insulation sleeves to permit the free circulation of air on all sides of the same, a perforate mica plate over said head to protect said lighting element and its support in lighting a cigar.
- 60 8. A cigar lighter comprising a heat resisting fire-proof insulation block having a sunken central portion on its upper side, a series of holes through said block within said sunken portion, two resistances, one of said resistances a resistance lighting element sewn through said series of holes in said block and connected to a source of electrical supply in series with the second resistance, a perforate mica plate attachable over said sunken portion to protect said lighting element, and fire-proof insulation support for 65 said lighting block on said head.
- 65 9. A cigar lighter comprising a case having ventilation openings therein, a neck of fire resisting metal on said casing, a lighter head attached on said neck at an angle of inclination, a heat insulation block in said 70 lighter head supported between fire-proof insulating composition blocks, the upper block having a concentrically arranged series of openings therethrough, a resistance element mounted in said casing, a resistance lighting element sewn through said opening and connected to a source of electrical supply in series with said resistance element in 75 said casing, said head having ventilating openings therethrough to draw the lighting heat therethrough, and a perforate mica plate on said head over said lighting element to protect the same.
- 80 10. In testimony whereof I have affixed my signature in the presence of two witnesses.
